3 Claims. (Cl. 121—120)

The present invention is concerned with devices for transmitting hydraulic power, of the kind in which the prime mover discharges a fluid which is introduced, at constant delivery, into a hydraulic motor controlling the member to be driven and whose delivery per revolution may be varied according to the load, whereby the speed of the hydraulic motor is varied and it is possible to strike a balance between the load and the driving torque.

The invention is more particularly concerned with a distributor for such a type of hydraulic motor. Such distributor is constituted by a slide valve the position of which controls the delivery per revolution of the hydraulic motor and, consequently, the speed of the driven member, one of the faces of said slide valve being subjected to the action of a fluid discharged by the prime mover and brought to a substantially constant predetermined pressure by a pressure control device, while its other face is subjected to the same pressure reduced, however, by the loss of head resulting from the entry of the fluid into the motor and which depends on the load on the motor, so that the position of the slide valve and, consequently, the speed of rotation of said motor, likewise depends on the load.

Other characteristics and features of the invention will become apparent from the ensuing description taken with reference to the accompanying drawings wherein:

Fig. 1 is a sectional elevation of a first embodiment of a hydraulic motor according to the invention.

Figs. 1a and 1b are views of the control cams along a—a and b—b of Fig. 1.

Fig. 2 is a cross section on the line II—II of Fig. 1.

Fig. 3 is a detail view of the automatic distributor.

Fig. 4 is a longitudinal section of a modified application of the invention.

Fig. 5 is a section along the line V—V of Fig. 4.

Fig. 6 is a sectional elevation of another application.

Fig. 7 is a section along VII—VII Fig. 6.

The hydraulic motor illustrated by way of example in Figs. 1—3, comprises the crank shaft 1, on the cranks 2 of which are mounted connecting rods 3a—3a, 3b—3b, 3c—3c, connected in pairs by the braces 4a, 4b, 4c. On said braces act the pistons of the motor which, in the example illustrated, are arranged in groups of three pistons disposed in star formation. The first of these groups is designated 5a, 5b, 5c; the second 6a, 6b, 6c and so on. The pistons such as 5a, 6a, 7a,

etc., may act on the brace 4a; the pistons such as 5b, 6b, 7b, etc., on the brace 4b; the pistons 5c, 6c, 7c, etc., on the brace 4c. It will be observed that this arrangement is only given by way of example and that each set of pistons might comprise any number of pistons other than three; an equal number of braces 4 would then be provided. Moreover, there may be any number of sets of pistons disposed in star formation. Finally, the pistons 5 of the first set have been illustrated as being of greater diameter than that of the pistons of the other sets, but this design is optional for the diameter may be the same for all pistons or may decrease from set to set.

This hydraulic motor receives fluid discharged by any appropriate means, such as a pump, not illustrated, driven by the motor whose power it is desired to transmit to the crank shaft 1.

The distributing mechanism according to the invention comprises for each longitudinal group of pistons such as 5a, 6a, 7a . . . , a slide valve 11 in the form of a differential piston, whose large piston 12 reciprocates in a cylinder 13 extending the length of the corresponding longitudinal row of pistons, while the small piston 14 reciprocates in a cylinder 15 in direct communication with the fluid inlet pipe 16.

In the duct 17 which connects the pipe 16 with the cylinder 13, is inserted a pressure control device, the purpose of which is to bring the fluid to the desired pressure and which comprises a piston 20 on which acts a calibrated spring 20a or any other mechanical, hydraulic or pneumatic restoring means. To reach the cylinder 13, the discharged fluid has to overcome the resistance of the spring 20a, whereby said fluid is brought to the desired pressure. In the duct 17 is likewise mounted an inlet valve 18, controlled by a distributing cam 19 set on the shaft 1. Said cam is common to the three inlet valves 18. The cylinder 13 communicates with the cylinders of the corresponding pistons through passages 5'a, 6'a, etc. The cylinder 13 likewise communicates with an outlet passage 21a in which is mounted a valve 21 actuated by a second cam 22. The cylinder 13 finally communicates at its left end with a second outlet passage 18a.

It will be observed that the slide valve 11 is subjected, on the one hand, in the cylinder 15 to the action of the fluid arriving through the pipe 16 and put under pressure by the pressure control device 20 and, on the other hand, in the cylinder 13 to the action of the same pressure reduced however, by the loss of head due to the fact that

said cylinder 13 communicates with one or more of the cylinders of the pistons 5a, 5a, etc.

The apparatus operates in the following manner: On starting, the slide valve 11 is in its right end position (position of Fig. 1) in which the cylinder 13 communicates solely with the cylinder of the piston 5a. Naturally, the cylinders of the pistons 5b, 5c of the same set communicate with the corresponding distribution cylinders 12. Consequently, the pressure fluid acts on the first set of pistons 5a, 5b, 5c which rotate the crank shaft 1 through the medium of the braces 4 and connecting rods 3. If the load on the crank shaft is such that the loss of pressure head in the cylinder 13, due to the flow of pressure fluid in the cylinders of the first set of pistons, 5a, 5b, 5c, exactly compensates the difference of the surface area of the pistons 12 and 14 of the slide valve 11, said slide valve will remain stationary and only the first set of pistons will operate rotating the crank shaft directly at the highest possible speed.

Should the load on the crank shaft 1 increase, its speed and the speed of displacement of the pistons 5 fall off, and the loss of pressure head in each of the cylinders 13 decreases. On this account, the pressure on the distributor piston 12 increases and the slide valve 11 moves to the left thus uncovering the passage 6'a, whereby the second set of pistons 5a is brought into circuit. If, consequent thereon, equilibrium is established between the pressure on the piston 14 and that on the piston 12, the slide valve 11 will come to rest in this position in which the two first sets of pistons 5 and 6 operate to drive the shaft 1 at a slightly lower speed than before. Should the loss of pressure head still decrease, due to the increase of load, the slide valve 11 uncovers other passages such as 7'a, 8'a, etc., bringing a greater number of pistons into circuit, whereby the speed of the crank shaft 1 is correspondingly reduced, such speed being thus proportional to the load on the crank shaft. In the usual manner, the admission of fluid to each cylinder is controlled by inlet and exhaust valves 18 and 21 actuated by the cams 19 and 22 and by the ducts 18a. The sole purpose of the three slide valves 11 which, theoretically, operate in synchronism, is to determine according to their position, which depends on the load, the number of sets of pistons which are brought into circuit.

The automatic distributing mechanism according to the invention may be applied to other than piston motors.

Thus, in Figs. 4 and 5, such mechanism has been shown applied to a hydraulic motor wherein each set of pistons is replaced by a set of receiving gears 23a, 23b, 23c, etc., on which the fluid acts to rotate them.

In the example illustrated, a distributor 11 is provided for forward drive and a distributor 11a for reverse drive, and the pump has been illustrated at 40. Said pump discharges the fluid through the duct 41. Said fluid acts on the pressure control device 20 which, in this case, likewise serves to reverse the drive. In the figure, it is represented in the position for forward drive, for, when it is displaced under the action of the fluid, it admits a fluid into the cylinder 13 but prevents access of the fluid (through the medium of its skirt 42) to the cylinder 13a, which for forward drive serves for the exhaust into an exhaust receiver formed by the chamber provided within the central portion of the frame. On the other hand, if the pressure control device 20 be

rotated through 180°, it is the cylinder 13a which receives the pressure fluid and the apparatus then operates in reverse.

The mechanism according to the invention may likewise be applied to motors of the type shown in Figs. 6 and 7, that is to say, which comprise a circular series of cylinders 24 set on the driving shaft 1 and in which reciprocate pistons 25 whose heads are connected to an eccentric member 26 whose eccentricity with respect to the axis of the shaft 1 may be varied by means of eccentrics 27 and 28. Such eccentricity may be varied by imparting a relative angular displacement to the eccentrics 27 and 28, for example, by means of the toothed pinions 29, 29a and the shaft 30. The pinion 29a is fixed on the shaft 30 and controls the eccentric 28 through the instrumentality of the toothed sector 33a which is secured to the latter; the pinion 29 is controlled by the pinion 29a and itself controls the sector 33 secured to the eccentric 27. Such relative angular displacement alters the throw of the outer eccentric 27 and hence of the member 26 which is mounted on said eccentric 27 on ball bearings 31. This is a known type of hydraulic motor. When the mechanism according to the invention is applied to said motor, it is only necessary to provide between the slide valve 11 and the shaft 30, a suitable mechanical connection through the medium of which the slide valve 11 as it moves controls the relative angular displacement of the eccentrics 27 and 28, and, consequently, the position of the member 26. On the position of this member depends the amplitude of the reciprocating strokes of the pistons 25 in the cylinders 24 and, consequently, the speed at which the driven shaft 1 is rotated. The mechanical connection may be constituted by a plain rod 31 which extends the slide valve 11 and which is connected in any suitable manner to a lever 32 set on the shaft 30.

It is evident, moreover, that the invention might be applied to other types of hydraulic motors, the essential characteristic of the invention residing in a slide valve which automatically takes up a position of equilibrium in which the motor to which it is applied rotates at a speed corresponding to the load on it.

I claim:

1. In combination with a motor adapted to be driven by hydraulic power, a distributor for controlling the supply of pressure fluid to said motor, comprising, in combination, a slide valve including two coupled differential pistons adapted to move in corresponding cylinders, interconnected fluid inlets for admitting fluid to the opposite ends of said cylinders, the larger of said cylinders communicating with said motor in such wise that while the smaller piston is subjected to the full pressure of said fluid the larger piston is subjected to said pressure reduced by the loss of head determined by the load on said motor, and pressure control means mounted in the fluid inlet to said larger cylinder for preventing admission of fluid into said larger cylinder until the pressure of the fluid has reached a predetermined value.

2. Apparatus according to claim 1, wherein the pressure control means comprise a piston valve and a spring tending to hold said piston valve in position to cut off the admission of fluid to the larger of said cylinders against the thrust exerted by said fluid on said piston valve.

3. Apparatus according to claim 1, in combination with a motor having a drive shaft, a cir-

cular series of cylinders set on said drive shaft, whereby the relative angular displacement of said two eccentric members alters the throw of said outer eccentric member, and a linkage mechanism for coupling said two superposed eccentric members to said slide valve to be controlled by the displacement of the latter.
